UNITED STATES PATENT OFFICE.

JOHN PETERKIN, OF BROOKLYN, NEW YORK.

DESIGN FOR A PUZZLE-BOX.

SPECIFICATION forming part of Design No. 26,163, dated October 6, 1896.

Application filed July 30, 1896. Serial No. 601,097. Term of patent 3½ years.

To all whom it may concern:

Be it known that I, JOHN PETERKIN, a citizen of the United States, residing at Brooklyn, in the county of Kings and State of New York, 5 have invented and produced a new and original Design for Puzzle Boxes or Cases, of which the following is a specification, reference being had to the accompanying drawings, forming a part thereof.

10 In the drawings forming part of this specification, Figure 1 is a plan view of my puzzle box or case; and Fig. 2, a transverse section thereof on the line 2-2 of Fig. 1, these two views being necessary to fully illustrate my 15 design.

The leading feature of my design consists of a rectangular box or casing provided with a bottom 5, sides 6, and ends 7, and said box or casing is square in form, and said box or 20 casing is provided with a false bottom 8, which is bent longitudinally, so as to form a central longitudinal groove 9 and two corresponding side grooves 10, which extend from one end of the box or casing to the other, 25 and by means of this formation of the false bottom corresponding longitudinal elevations 11 are formed between the side grooves 10 and the central groove 9, which also extends from one end of the box or casing to 30 the other, and arranged in the center of the bottom 8 is a picture or the representation of a house, as shown at 13, and said house is

inclosed at each corner by short vertical flanges or walls 14, the central portions of which are curved outwardly and the outer 35 ends inwardly, as clearly shown in Fig. 1.

The picture or representation of the house may be printed, painted, stamped, engraved, or otherwise formed on the bottom 8, and that portion of the said bottom within the walls or 40 flanges 14 is colored differently from the other portions thereof, and one half of the bottom is also differently colored from the other half and from that portion within the walls or flanges 14.

The space within the vertical walls or flanges 14 is oblong in form and arranged transversely of the central longitudinal groove 9, and the entire design is symmetrical and regular in form.

Having fully described my new and original design, what I claim as new, and desire to secure by Letters Patent, is—

The design for puzzle boxes or cases, herein shown and described.

In testimony that I claim the foregoing as my invention I have signed my name, in presence of the subscribing witnesses, this 27th day of July, 1896.

JOHN PETERKIN.
